UNITED STATES PATENT OFFICE.

FRANCIS J. TORRANCE, OF ALLEGHENY, PENNSYLVANIA, ASSIGNOR TO STANDARD SANITARY MFG. CO., OF PITTSBURG, PENNSYLVANIA, A CORPORATION.

WATER-CLOSET.

No. 906,470.

Specification of Letters Patent.

Patented Dec. 8, 1908.

Application filed March 25, 1907. Serial No. 364,219.

To all whom it may concern:

Be it known that I, FRANCIS J. TORRANCE, a citizen of the United States, residing at Allegheny, in the county of Allegheny and 5 State of Pennsylvania, have invented certain new and useful Improvements in Water-Closets, of which the following is a specification.

This invention has relation to water closets, and has for its object the provision of a water closet of novel construction particularly adapted for use in jails, penitentiaries and similar institutions.

The principal object of my invention is to 15 provide a water closet which will be supported above the floor of the cell or other apartment, without resting on or touching the floor.

In carrying my invention into effect, I 20 provide a water closet having an integral siphon outlet and drag leg, the latter being provided at its outlet end with a vertical flange by means of which the closet is attached to a vertical flange carried by a 25 branch of a soil pipe disposed within the wall line of the cell or apartment.

In the accompanying drawing in which I have illustrated my invention: Figure 1 is a plan view showing the closet attached to the 30 soil pipe. Fig. 2 is a vertical sectional view of the same. Fig. 3 is a rear elevation, partly in section, of the closet detached from the soil pipe.

The bowl of the closet is designated 1 and 35 is provided with the flushing rim 2, which is formed of a separate piece from the bowl as shown. The bowl 1 is formed with a siphon outlet comprising the up limb 3, and the down limb 4, and the latter opens into 40 a drag leg 5, which is formed integral with the siphon outlet and the bowl, the outlet end of the drag leg being disposed horizontally as shown at 6, and surrounded by a vertically disposed flange 7. The flange 7 is 45 substantially oval in shape, as clearly shown in Fig. 3, and extends up to a point substantially in alinement with the upper surface of the flushing rim 2. The flange 7, is formed with a number of holes 8, which 50 serve to receive bolts 9 by means of which the flange 7 is attached to a similarly shaped vertically disposed flange 10, carried by the substantially horizontally disposed branch 11 of a soil pipe 12. A vertical rib 13 is 55 formed integral with the flange 10, the

branch 11 and the soil pipe 12, and serves to strengthen these parts and assists in withstanding the strain to which they are subjected by the weight of the water closet. The flange 7 is provided with an integral 60 vertical rib 14 which connects the upper part of this flange and the upper portion of the siphon outlet and serves to strengthen these parts. The outlet end 6, of the drag leg terminates in a flange 15 which protrudes beyond the flange 7 and extends into the branch 11 of the soil pipe 12. The floor line of the cell or apartment is designated 16 and the wall of the same 17 and the soil pipe 12 being as shown, located outside of 70 the wall line with the flange 10 nearly flush with the wall line, the surface of the flange 7 will coincide with such wall line. A flexible gasket 18 is interposed between the flanges 7 and 12 to secure a water tight joint. 75

The closet being constructed as described and shown is, it will be observed, supported a considerable distance above the floor and entirely clear of the same and conforms to the standard sanitary requirements in all 80 particulars, there being no floor connections to permit lodgment of dirt and the floor below the closet being readily accessible for scrubbing and the closet bowl, siphon outlet and drag leg being in a single piece devoid 85 of all joints between the bowl and the flange on the branch of the soil pipe.

I claim:

1. The combination of a water closet having an integral siphon, a drag leg, a rearwardly extending horizontal outlet extension, a pierced flange surrounding said outlet extension and a web extending from the apex of the siphon and connecting the said flange with the siphon and outlet extension, 90 with a soil pipe having a horizontally disposed branch, a vertical pierced flange carried by said branch, bolts extending through both said flanges and a web connecting the flange on the said branch with the soil pipe. 95

2. The combination of a water closet having an integral siphon extension and drag leg terminating in a horizontal outlet, a vertical, pierced, flange surrounding said outlet, a web extending from the apex of said 105 siphon and connecting said flange and said siphon extension, with a soil pipe having a horizontal branch, a vertical flange surrounding said branch, bolts extending through said flange and an integral web 110

connecting the flange on said branch of the soil pipe with the vertical portion of the soil pipe.

3. The herein described closet, comprising the bowl 1 having formed integral therewith and projecting rearwardly therefrom an outlet extension containing the siphon up limb 3, siphon down limb 4, drag leg 5, and upwardly extending terminal 6, the last named 10 being provided with the external flange 7 and with the strengthening web 14 extending from the apex of the siphon and adapted and designed to be secured to the soil pipe extension and to wholly support the closet bowl above the floor.

4. A water closet structure comprising a bowl, siphon, and drag leg, composed of an integral casting having the siphon and drag

leg portion extended rearwardly of the closet bowl, and terminating in a horizontal 20 boss leading to the soil pipe, said siphon and drag leg extension being formed with a flange surrounding said boss, and with a vertical web extending from the apex of the siphon to the face of said flange, the flange 25 being pierced for bolts, and constituting the sole means by which the closet, siphon and drag leg are supported above and independently of the floor.

In testimony whereof I affix my signature, 30 in presence of two witnesses.

FRANCIS J. TORRANCE.
